(57) **CLAIM**

The ornamental design for a hinge for spectacles, as shown and described.

DESCRIPTION

FIG. 1 is a perspective view of the hinge according to our design;

FIG. 2 is a top plan view of the hinge of FIG. 1;

FIG. 3 is a bottom view of the hinge of FIG. 1;

FIG. 4 is a right side elevational view of the hinge of FIG. 1;

FIG. 5 is a left side elevational view of the hinge of FIG. 1;

FIG. 6 is a front elevational view of the hinge of FIG. 1;

FIG. 7 is a rear elevational view of the hinge of FIG. 1;

FIG. 8 is a top view of the hinge of FIG. 1 attached to the left side of a pair of spectacles;

FIG. 9 is a perspective view of the hinge of FIG. 1 attached to the left side of a pair of spectacles; and,

FIG. 10 is an additional perspective view of the hinge of FIG. 1 attached to the left side of a pair of spectacles.

The broken lines of FIGS. 7–10, showing a part of the spectacles, are for environmental structure only and form no part of the claimed design.

1 Claim, 10 Drawing Sheets
